UNITED STATES PATENT OFFICE.

CHARLES REINEKE, OF NEW YORK, N. Y.

INTERNAL-COMBUSTION ENGINE.

Application filed October 1, 1920. Serial No. 414,049.

To all whom it may concern:

Be it known that I, CHARLES REINEKE, a citizen of the United States, residing at New York, in the county of New York and State of New York, have invented certain new and useful Improvements in Internal-Combustion Engines; and I do hereby declare the following to be a full, clear, and exact description of the invention, such as will enable others skilled in the art to which it appertains to make and use the same.

This invention relates to internal combustion engines of a multi-stroke type set forth in my application Serial Number 311,976, filed July 19, 1919, wherein a plurality of strokes of the piston is obtained for every revolution of the power shaft.

An object of the present invention is to provide a novel form of power transmitting means adapted to receive the reciprocatory movement of opposed pistons and translate the same into a relatively slow rotary movement, the said means including a novel form of cam element and offset connection for increasing the leverage and accelerating the movement of the opposed pistons at their innermost points of travel.

Another object of this invention is to provide means for maintaining a timed relation between the oppositely arranged pistons in adjacent cylinders.

With these and other objects in view the invention further consists in the comparatively simple construction and arrangement of the several parts hereinafter described and pointed out in the appended claims.

In the accompanying drawings wherein similar reference characters designate corresponding parts in the several views,

40 Figure 1 is a vertical sectional view through my improved type of engine; and

Figure 2 is a transverse sectional view through one of the cylinders on the line 2-2 of Figure 1.

45 Referring to the drawings, the present invention includes among other things a housing 1 to which the cylinders 2 may be secured or cast integral; associated pistons 3 and 4 arranged in opposed relation in each cylinder; a power transmitting device 5 interposed between the pistons and the power shaft; and means comprising the lever mechanism 6 for maintaining the pistons of adjacent cylinders in timed relation.

50 The engine is supplied with fuel by forc-

ing the same by auxiliary or crank case compression between the pistons or in any other approved manner, and the exhaust thereof is controlled by any suitable device, as will be understood. It will also be understood that any number of cylinders can be utilized and various cycles of operation provided.

The lower pistons 3 are each provided with a roller 7 carried by a shaft 8 journalled in bearings 9. The roller is freely revolvable upon the shaft 8 as will be understood. As shown in Figure 2, the roller is preferably located off center with relation to a vertical axis through the power shaft, thereby regularly imparting movement to the cam elements to be presently described, and overcoming all tendencies of the engine to hang on a dead center. It will also be apparent that the location of the roller serves to give a definite path of direction to the cam elements, and permit of the pistons transmitting a maximum power stroke thereto by increasing the leverage near the end of each stroke.

The roller extends slightly beyond the pistons 3 as shown.

Cooperating with the rollers 7 are cam elements 10 formed with diametrically extending arms or wings, the outer ends of which are curved as indicated at 11 to more effectively co-act with said rollers.

Other rollers 12 are cooperatively associated with each of the cam elements 10, said rollers being off-set upon the opposite side of the vertical axis through the power shaft as best shown in Figure 2.

The rollers 12 are revolvably supported in a movable frame or section 13 provided with rods or arms 14 extending from the housing 1 and connected to the uppermost piston 4, as at 15. This frame section is guided within the housing in any suitable manner.

Another frame section 16 is secured to the lowermost piston 3 and comprises a transverse bar 17 having depending guide members 18. Plates 19 bolted to the housing 1 serve to guide the frame sections as will be understood. Other guides may also be provided, and I do not limit myself to the exact construction herein set forth.

The means for maintaining the opposed pistons of adjacent cylinders in their respective timed relation comprises the levers 6 pivotally mounted at 20 and 21 in respec-

tive bearing supports 22 and 23. The levers are pivoted intermediate their ends, which latter are designed to bear against the respective frame sections 13 and 16 and upon 5 each reciprocation of the pistons, the levers are rocked upon their pivots. There may be separate sets of levers, or the respective ends of each lever may be bifurcated sufficiently to engage the frame sections or pistons as 10 will be understood.

In operation the levers 6 are designed to maintain a co-related travel with respect to the pistons in adjacent cylinders, and when the engine is at rest, prevent the movement 15 or settling of any one of the pistons into a position which would untimely the power strokes. This form of lever control for keeping the pistons in timed relation is designed for use where a number of cylinders 20 are provided in the motor.

The power shaft 24 is of ordinary construction and is journalled in bearings 25 carried by the housing 1. Any type of mechanism can be coupled to the power shaft 25 24 as will be understood.

In the operation of the engine the opposed pistons 3 and 4 are separated by the explosion of the fuel charge therebetween, and the rollers 7 and 12 are moved against the 30 arms of the cam elements 10 secured to the shaft 24, thereby revolving the same. In the form of engine shown herein the cam elements of adjacent cylinders are set at ninety degrees so as to permit of smooth operation 35 and the steady application of power to the shaft 24. It will be seen from the construction of the cam elements that two complete reciprocations of the pistons are necessary to impart a single revolution to 40 the power shaft, but it will be understood that a greater number of arms or wings can be arranged upon the cam elements for obtaining a greater number of piston strokes for every revolution of the power shaft.

45 While I have shown the rollers 7 and 12 provided on the pistons 3 and frame section 13, respectively, it will be understood that any form of anti-friction device may be employed, and further that such device or 50 rollers can be carried by the elements secured to the power shaft.

Various changes in the construction and arrangement of the several parts may be made without departing from the spirit of 55 my invention, and I do not limit myself to the exact form disclosed herein.

I claim:

1. An internal combustion engine including a plurality of cylinders, a pair of opposed pistons arranged in each cylinder, a power shaft arranged beyond the portions of the bores of the cylinders in which the pistons move, cams arranged on said shaft, and oppositely arranged rollers connected 60 to each pair of pistons and engaging each 65

of said cams, said rollers being arranged in offset relation relatively to the axis of the cylinder with which they are associated.

2. In an internal combustion engine, a plurality of cylinders, a pair of opposed 70 pistons arranged in each cylinder, a pair of rollers operatively connected to each pair of pistons and offset relatively to the axis of the cylinder with which they are associated, a power shaft, a plurality of cams arranged 75 on said power shaft and each cam operatively engaging the rollers of each pair of rollers, each of said cams being so shaped as to require a multiplicity of power strokes of each piston of each pair of pistons to impart a complete revolution to the cam associated with the last mentioned pair of pistons.

3. An internal combustion engine including a plurality of cylinders, a pair of opposed pistons arranged in each cylinder, a movable frame associated with each piston of each pair of pistons, a pair of rollers actuated by the pistons of each pair of pistons, cams actuated by said rollers and constructed to require a multiplicity of power strokes of a single pair of the opposed pistons to impart a single revolution to one of the cams, a power shaft actuated by said cams, and rocking levers connecting the movable frames of the pairs of pistons for causing movement of the pair of pistons of one cylinder towards each other to impart movement to the pair of pistons of the other cylinder away from each other. 100

4. An internal combustion engine including a cylinder, opposed pistons arranged in said cylinder, oppositely disposed rollers operatively connected with said pistons and offset relatively to the axis of the cylinder, a power shaft intersected by the axis of said cylinder, and radially arranged arms mounted on the power shaft and engaging said rollers, said arms forming a cam of such shape as to require a multiplicity of power strokes of the pistons to impart a single revolution to the power shaft. 105

5. In an internal combustion engine, an open ended cylinder, opposed pistons arranged in said cylinder, a power shaft arranged beyond the portion of the bore of the cylinder in which the pistons move, a cross-head connected to the piston which is furthest away from the power shaft, a roller carried by said cross head, a roller connected to the piston which is nearest the power shaft, and a cam mounted on said power shaft and engaging said rollers, said cam being constructed to require a multiplicity of power strokes of the piston to impart a single revolution to the power shaft, and said rollers being offset relatively to the axis of said cylinder. 115

6. An internal combustion engine including a plurality of cylinders arranged side 120

- by side, a pair of opposed pistons arranged in each cylinder, a cross head connected to each piston of each pair of pistons, a power shaft, a rocking lever operatively connecting the cross head of the piston of one of said cylinders which is nearest the power shaft to the piston of the other cylinder which is nearest the power shaft, another rocking lever connecting the cross heads of the pistons which are furthest from said shaft, and a cam and rollers operatively connecting the pistons of each pair to the power shaft and so constructed as to require a multiplicity of power strokes of each pair of pistons to impart a single revolution to one of the cams. 15
- In testimony whereof I affix my signature in presence of two subscribing witnesses.
- CHAS. REINEKE.
